UNITED STATES PATENT OFFICE.

JOHN H. FLAGLER, OF NEW YORK, N. Y.

ROOF OF FURNACES.

SPECIFICATION forming part of Letters Patent No. 325,403, dated September 1, 1885.

Application filed January 31, 1884. (No model.)

To all whom it may concern:

Be it known that I, JOHN H. FLAGLER, of New York, in the county of New York and State of New York, have invented a new and useful Improvement in the Construction of the Roofs of Tube-Welding and other Furnaces; and I do hereby declare the following to be a full, clear, and exact description thereof.

My invention relates to the construction of furnaces, having special reference to the furnaces employed for heating plates or skelp in the manufacture of wrought-metal tubing.

In regenerative gas-furnaces it has been found that where the furnace-roof was arched, as the gas and air were not thoroughly intermingled at the side or end where they entered the furnace-chamber, complete combustion did not take place at that side or end of the chamber, and as the chamber increased in size the center was not highly heated, but a high heat was obtained at the opposite side or end thereof just before the products of combustion entered the ports to pass through the regenerators to the stack, and in these chambers much of the heat in the center thereof was obtained from the radiation or reverberation of the heat from the roof down into the metal. To overcome this in small furnaces—such as puddling or open-hearth furnaces—30 the roof was given the form of an inverted arch, so that the gas, air, and flame were thrown by the sloping roof down into the furnace bed or hearth, and this form of furnace has given much better results, as the gas and air were more thoroughly intermingled by contact with this sloping roof, and the flame was brought into direct contact with the metal or glass to be heated or melted; and as the furnace-chamber was not so high in the center 40 this was the hottest part of the chamber. These inverted or depressed roofs could be easily formed in small furnaces, as the inverted arch could be supported by a regular arch at right angles thereto, or the central or key course of the inverted arch could extend above the roof and be supported by a rod passing through holes therein and supported by the furnace-walls. In single-draft heating and puddling furnaces the roof has been supported 50 by a curved or arched "metal bearer," having its ends resting on the furnace-roof, and provided with rods extending down and fit-

ting around a longitudinally-extending bar bent to the curve of the roof, said bar supporting a key-course of brick from which the roof is built to the furnace-walls. In long furnaces employed for heating or welding skelp or tubing, and certain smelting furnaces, however, it is necessary that the roof be of substantially the same height the whole length 55 of the furnace, and as the furnaces are from eighteen to fifty feet in length, this inverted arch cannot be supported by the regular arch at right angles thereto, and neither the rod passing through holes in the key-brick and 60 supported by the furnace-walls, nor the curved or arched metal bearer extending longitudinally of the furnace and resting on the roof, from which metal bearer the bar is suspended, could be practicably employed to support the 65 key-course. In some large double heating-furnaces the same difficulties are also encountered. In tube-furnaces this regular arched roof is found exceedingly objectionable, as the 70 heated skelp is pushed from the center of the chamber, and is heated there only by the heat radiated or reverberated from the upper part of the chamber, so that it is difficult to raise it to the required heat for welding, while if the skelp is heated at the side of the chamber 75 where the greatest heat is generated there is a liability of the iron being too highly heated, or burned, and the skelp is so soft that it cannot be brought to the center to be delivered to the rolls without losing its shape. For 80 these reasons an efficient and practicable means of building the roofs of these large or long furnaces with an inverted arch is extremely desirable.

My invention consists, essentially, in supporting the central or key course of these inverted-arch roofs by means of a hollow holder within which the brick or tile fit, said holder being hung from beams or girders extending across the furnace above the roof and resting 85 on the furnace-walls, the key-course so supported forming the skew-backs from which the roof-walls are built to the outer furnace-walls.

It also consists in supporting the key-course 90 of the long furnace-roofs by a series of holders and supporting each holder separately from the furnace-walls, the weight of the roof being thus distributed over different parts of the

walls, and all injury thereto from expansion, contraction, or warpage of the key-course holders or their supports by the heat of the furnace being overcome.

5 To enable others skilled in the art to make and use my invention, I will describe the same more fully, referring to the accompanying drawings, in which—

Figure 1 is a cross-section of the tube-welding furnace, illustrating my invention. Fig. 2 is a longitudinal central section of a portion of the furnace. Fig. 3 is a top view of the same. Fig. 4 is a perspective view of the box holding the key-course of tile. Fig. 5 is 15 a cross-section of a furnace showing another form of the holder and key-course supported thereby.

Like letters of reference indicate like parts in each.

20 In the drawings, *a* represents the furnace-chamber; *a'*, the hearth or bed; *b*, the side or end walls from which the roof is thrown; *c*, the air-ports, and *d* the gas-ports over the side of the chamber *a*, these ports leading to the 25 generators. These parts are of the usual or any approved construction. The furnace-walls are built up above the points where the roof-walls rest on them, as at *b'*, and are topped by the plates *b'*, and on these walls are supported the beams or 30 girders *e*; and to allow for expansion or contraction of these girders because of the heat rising from the furnace and to overcome friction, they are supported on rollers *e'*, resting on the top plates, *b'*, so that all strain to 35 the furnace from such cause is overcome. From these girders *e* are hung or supported the key-course holders *f*, within or by which are held the key-course *H* of brick or tile, which forms the skew-backs or abutments 40 from which the roof-arches on either side are thrown to the furnace-walls *b*—or, in other words, the keystone or key course of the inverted arch of the roof.

The means preferred by me for supporting 45 these parts are as follows: Over the center of the furnace the girders *e* are re-enforced, as at *e'*, and bolt-holes formed through them, and the holders are hung from these girders by heavy bolts *g*, passing through these bolt-holes 50 and secured therein by nuts *g'*. The holders *f*, preferred by me, are shown in Figs. 1 to 4, and are formed of cast metal and made the length of each course-section or roof-section *k* in the furnace-roof, being generally from 55 five to seven feet long, and the required number being employed in each furnace, according to its length. It has the dovetail or equivalent recess *l*, in which the upper portion of the key blocks or tile *h* fit, these tile *h* being 60 formed double-dovetailed, and one portion fitting within the holder, while the other portion hangs down above the furnace-chamber to form the key of the inverted arch, as above referred to, the faces *h'* of these blocks forming 65 the skew-backs of the roof-arches *m*, which are built of the usual brick-work, over to the walls *b*, the opposite ends of the arch resting

on the skew-backs *b'* on said walls. To connect the holders *f* to the bolts, I cast on the top thereof the ribs *f'*, having recessed slots 70 or seats *p* formed therein, corresponding to the heads of the bolts *g*, and these bolt-heads fit into the seats, thus hanging the holder and its tile course *H* above the furnace-chamber. The ribs may be strengthened by the cleats *p'* 75 or other means, as desired. The under surface of the key-course *H* has the same curve as the inverted arch, so that this key-course forms part of the depressed roof, whether it be formed of single central blocks or of several 80 shape-blocks.

In building the furnace the key-course *H*, supported as above described, is adjusted by the nuts *g'* to the desired height above the furnace-bed in the tube-welding furnaces, the 85 center of the depressed roof being about one-half the height of the regular arched roof heretofore employed. Each section *k* of the key-course is supported separately, and if any special angle is to be given to the roof the 90 section may be adjusted accordingly. The builder then throws the roof from the central key-course over to the skew-back on the furnace-walls and can impart to the roof any curve or slope desired. The roof portions may 95 be built in sections in the same manner as the key-course is formed, and where the roof or some portion of it requires frequent rebuilding this is desirable, as it prevents any disturbing of the other portion thereof. Where, however, the roof remains for a long period it is not necessary to form it sectional, the 100 sectional key-course allowing for any shrinkage, expansion, or warpage of the sectional course or its supports. After the building of the 105 roof, it is clamped tightly together by means of the bolts *r'* passing through the brick stays *r* of the furnace. This construction of furnace-roof is preferred by me, as it requires but one 110 shape-brick, namely, the double-dovetail brick, fitting in the dovetail recesses in the holder. The holder *f* is also entirely above the roof, and is therefore but little exposed to the heat of the furnace and is surrounded by the air, so that any heat passing up through the brick-work is quickly carried off, and for these 115 reasons it is not as liable to warpage as where it is inclosed within the brick-work of the roof.

In Fig. 5 is illustrated another form of my 120 improved roof, which will be make the subject of a separate application. This construction is also found efficient for the purpose and to possess some special advantages. In this figure the principal portion of the roof over 125 the furnace-chamber is formed of these special shape brick or tile supported by the holder. The holder *f''* is divided longitudinally into two parts, *s s*, to allow for expansion and contraction thereof, each part being supported by the bolts *g* and girders *e* in the manner above described. Within the holder are two 130 shape-bricks, *t t*, fitting against the inner faces thereof and around a portion of the bases, and

between these bricks t is the wedge-brick t' , which wedges them against the dovetail sides thereof. The parts s of the holder are provided at the base with the longitudinal web s' , and the shape-bricks t^2 fit against the outer faces of the holder and around these webs s' , being thus supported thereby, the holders thus supporting a much broader key-course, H^2 , above the furnace-chamber. As these shape-
brick are liable to crack or break along the line where they are recessed to fit around the holder on account of uneven expansion or contraction, to distribute the weight of the roof-arches over the entire surface of the central course, I employ the face-blocks u , and build the arch of common brick from these face-blocks to the side walls.

It is evident that by my invention I am enabled to build these furnaces with inverted-
arch roofs of any desired width, curve, or slope, and any length, and that, therefore, all the advantageous results heretofore obtained from them in small furnaces may be obtained in large heating and long smelting or tube-welding furnaces. Practical use has shown that in tube-welding furnaces with such roofs the greatest heat is thrown to the center of the hearth, and that therefore the furnace can be operated much more advantageously, the tubes being inserted at the sides and moderately heated and then brought to the center under the depressed roof, where they are subjected to the direct contact of the flame and highest heat just before they are delivered to the rolls.

As the highest heat is in the center of the chamber, and the tubes are heated by direct contact of the flame instead of radiation, the furnace can be operated with less fuel.

I am aware that the roof of an annealing-kiln for flattening glass has been supported by a metal girder extending across the center of the kiln and braced or partly supported by a rod extending down from a cross-beam, the girder extending below the brick-work of the roof; but this metal girder could not be employed in regenerative furnaces where the heat is intense, as it would melt in a few hours and drop the roof, and even in low-heat furnaces the girder would be liable to warp and soon cause the straining and breaking of the roof.

By my invention these difficulties are entirely

overcome, as the key-course of brick-work is supported by a holder hung entirely from girders or cross-beams resting on the furnace-walls, and hence can be arranged in any desired position, and the brick-work only is exposed to the heat of the furnace, the metal holders of the key-course being fully protected thereby, and the roof will consequently withstand very high heat. As the key-course is supported in sections, the warpage of the holder supporting each section is not appreciable, and does not affect the roof, and the inverted roof may be made of any length desired.

What I claim as my invention, and desire to secure by Letters Patent, is—

1. In furnace-roofs, the combination of a holder hung from above the roof and having a dovetailed or similar recess therein, one or more courses of brick or tile supported by said holder and forming the central or key course of the roof, and roof-arches extending from said key-course to the furnace-walls, substantially as and for the purposes set forth.

2. A furnace roof formed of a central or key course of brick-work and courses of brick-work extending therefrom to the furnace-walls, said key-course being formed in sections supported by a series of holders having a dovetailed or similar recess therein, and said holders being supported separately by transverse beams extending across the furnace and resting on the furnace-walls, substantially as set forth.

3. In furnace-roofs, the combination, with the holder f , supported from above the roof and having the dovetailed recess l , of the double-dovetailed brick or tile fitting therein and extending below the holder to form the key of the inverted arch, substantially as set forth.

4. In furnace-roofs, the combination, with the furnace-walls, of the rollers e^2 on the top of said walls, the beams or girders resting on said rollers, and the key-course holder hung from said beams and supporting the key-course of the roof, substantially as and for the purposes set forth.

In testimony whereof I, the said JOHN H. FLAGLER, have hereunto set my hand.

JOHN H. FLAGLER.
